PEDESTAL FOR A SEAT

Chester J. Barecki, Grand Rapids, Mich., assignor to
American Seating Company, Grand Rapids, Mich.

Filed May 12, 1975, Ser. No. 576,680

Term of patent 14 years

Int. Cl. D6—06

U.S. Cl. D6—194

FIG. 1.

FIG. 2.

FIG. 3.

FIG. 4.

FIG. 1 is a side perspective view of a pedestal for a seat showing my design;

FIG. 2 is a front elevational view of the pedestal of FIG. 1;

FIG. 3 is a side elevational view of the pedestal of FIG. 1; and

FIG. 4 is a top, plan view of the pedestal of FIG. 1.

I claim:

The ornamental design of a pedestal for a seat, as shown.
